UNITED STATES PATENT OFFICE

CLYDE W. KELLY, OF DETROIT, MICHIGAN, ASSIGNOR TO DETROIT STEEL PRODUCTS COMPANY, OF DETROIT, MICHIGAN, A CORPORATION OF MICHIGAN

OPERATOR FOR WINDOWS

Application filed December 31, 1928. Serial No. 329,533.

The invention relates to operators for windows and refers more particularly to operators for screened windows, in which the screens are located at the inner sides of the windows. One of the objects of the invention is to provide means for closing the opening in the screen providing for the passage of the means for actuating the ventilator. Another object is to provide a closure member for the screen opening movable to allow the ventilator actuating means to assume various angular positions. Further objects of the invention reside in the novel features of construction of the operator and its support and the combinations and arrangements of parts as more fully hereinafter set forth.

In the drawings:—

Figure 1 is an interior side elevation of a window embodying my invention;

Figure 2 is a cross section on the line 2—2 of Figure 1;

Figure 3 is a cross section on the line 3—3 of Figure 2;

Figure 4 is an interior side elevation of a portion of the window with the operator removed;

Figure 5 is a view similar to Figure 2, showing a modified construction;

Figure 6 is a cross section on the line 6—6 of Figure 5;

Figure 7 is a view similar to Figure 4, showing a modified construction.

The invention is particularly applicable to windows having swinging ventilators, such as casement windows, which latter is shown in the present instance. 1 is the frame having an opening and 2 is the ventilator for the opening, this ventilator being pivotally mounted at one side upon a side bar of the frame. 3 is the screen located at the inner side of the frame and detachably held thereagainst by suitable means, such as the clips 4, upon the frame engaging the top and bottom bars of the screen frame. The bottom bar 5 of the screen frame is formed with the opening 6 therethrough for the passage of the means for actuating the ventilator.

The ventilator operator includes the support 7 and the rod 8 slidably engaging the

support and having the curved end 9 connected to the ventilator by means of the bracket 10 rigidly secured to the inner side of the bar of the ventilator and extending inwardly therefrom. The connection between the rod and bracket is formed by the pivot 11, which extends through a portion of the curved end reduced in thickness so that the lower face of the bracket is substantially flush with the remaining portion of the rod. 12 is a bracket rigidly secured to the inner side of the bottom bar of the frame 1 and having a lateral inwardly extending portion 13 spaced below the bottom screen bar 5 and an upwardly extending portion 14 extending parallel to and spaced slightly from the inner side of the bottom screen bar. The upwardly extending portion 14 is provided with the longitudinally extending elongated opening 15 having the notch 16 at its lower edge. 17 is a laterally extending plate passing through the notch 16 and rigidly secured to the lateral portion 13 of the bracket 12, the inner end of this plate being pivotally connected to the rod support 7 at 18 for supporting the same.

With the arrangement as thus far described, the ventilator actuating rod 8 may extend substantially parallel to the screen when the ventilator is in closed position, as shown particularly in Figure 3. By swinging the actuating rod and its support 7 about the pivot 19 leverage is provided for initially opening the ventilator, after which the rod may be longitudinally moved in its support to continue the opening of the ventilator, the rod and support during this opening movement continuing to swing about the pivot. The elongated opening 15 in the upwardly extending portion 14 of the bracket 12 and also the elongated opening 6 in the bottom screen bar readily permit this angular movement.

For the purpose of closing the opening 6 in the bottom screen bar and also the opening 15 in the bracket 12, I have provided the closure member 20, which is longitudinally slideable upon the bracket 12. This closure member is preferably formed of sheet metal and has the opening 21 therethrough for the pas-

sage of the actuating rod 8. This closure member has its upper portion bent laterally inward and then downward to embrace the upper edge of the upwardly extending portion 14 of the bracket 12 to assist in supporting and guiding the closure member. The closure member is also preferably provided with the inwardly extending flanges 22 at the upper and lower edges of the opening 21 and extending into the opening 15 of the upwardly extending portion of the bracket 12 to assist in guiding the closure member. The closure member, being slideable longitudinally upon the bracket, permits angular movement of the actuating rod 8 and at the same time closes the opening 6 in the bottom screen bar.

In the modification shown in Figures 5, 6 and 7, the arrangement of parts is very similar with the exception of the support for the ventilator operator and the means for guiding the closure member for the opening in the bottom screen bar. As shown, the support for the ventilator operator comprises the bracket 23, which is rigidly secured to the inner side of the bottom bar of the frame 1' and has the outer laterally extending portion 24 and the inner laterally extending portion 25, the latter being elevated to a height above that of the former and being pivotally connected to the operator rod support 7'. 26 is a plate preferably formed of sheet metal and having a depending portion 27 clamped between the inner side of the bottom bar of the frame 1' and the adjacent portion of the bracket 23, a portion 28 supported upon the laterally extending portion 24 and an upwardly extending portion 29 extending parallel to but spaced from the inner side of the bottom bar 5' of the screen. This plate has depending beads 30 with spaced side walls at opposite ends of the laterally extending portion 24. The upwardly extending portion 29 of the plate is formed with the longitudinally extending elongated opening 31 providing for the passage of the operator rod and has its upper portion bent outwardly and then downwardly to form a downwardly opening channel. The closure member is in the nature of a sheet metal plate 32 having an opening 33 for the passage of the operator rod and having at the ends of its lower edge the projections 34. The upper edge of this closure member slidably engages in the downwardly opening channel formed in the upper edge of the upwardly extending portion 29 and the projections 34 of this closure member slidably engage in the beads 30. It will thus be seen that this closure member closes the opening in the bottom screen bar and incidentally the opening in its guide.

From the above description it will be seen that I have provided an operator for actuating the ventilator of a window which is so constructed that the motion of its parts con-

nected to the ventilator is substantially continuous and easily effected during both the opening and closing of the ventilator. It will also be seen that I have provided a simple construction of closure for the opening in the screen through which the operator rod extends, this closure providing for angular movement of the operator rod.

What I claim as my invention is:

1. An operator for the movable ventilator of a window having a screen located at the inner side of the window frame and provided with an opening, comprising a member connected to the ventilator and extending through the opening in the screen, mounting means for said operator including a support upon which the operator is movable and a bracket secured to the inner side of the window frame and pivotally carrying said support, and a closure carried by said bracket and movable relative thereto upon angular movement of said support for closing the screen opening. 75

2. An operator for the movable ventilator of a window having a screen located at the inner side of the window frame and provided with an opening, comprising an arm connected to the ventilator and extending through the opening in the screen, mounting means for said arm including a guide slidably engaged by the arm, a bracket secured to the inner side of the window frame and means upon said bracket for pivotally supporting said guide, and a closure member slidably mounted upon said bracket for closing the screen opening. 90

3. An operator for the movable ventilator of a window having a screen located at the inner side of the window frame and provided with an opening, comprising an arm connected to the ventilator and extending through the opening in the screen, mounting means for said arm including a guide slidably engaged thereby and a bracket secured to the inner side of the window frame for pivotally supporting said guide, a second bracket secured to the inner side of said window frame and having a portion extending transversely of said arm and formed with an opening for the passage of said arm and a closure member slidably engaging said second bracket and provided with an opening for the passage of said arm, said closure member closing the screen opening. 105

4. An operator for the movable ventilator of a window having a screen located inwardly of the ventilator and provided with an opening, comprising a member connected to the ventilator and extending through the opening in the screen, and means upon the window frame located inwardly of and spaced from the screen for mounting said operator for sliding and swinging action therewith. 125

5. An operator for the movable ventilator of a window having a screen located inwardly 130

of the ventilator and provided with an opening, comprising an arm connected to the ventilator and extending through the opening in the screen, a closure for the opening in the screen mounted for sliding movement, and means fulcruming the operator upon a stationary support at a point spaced inwardly from the said closure permitting swinging movement of the operator relative to the screen.

6. An operator for the movable ventilator of a window having a screen located inwardly of the ventilator and provided with an opening, comprising an arm connected to the ventilator and extending through the opening in the screen, a closure for the opening in the screen mounted for sliding movement and positioned inwardly of the screen, and means for fulcruming the operator upon a substantial part of the window frame at a point spaced inwardly from the said closure.

7. An operator for the movable ventilator of a window having a screen located inwardly of the ventilator and provided with an opening, comprising an arm connected to the ventilator and extending through the opening in the screen, means for supporting the screen including a bracket secured to the inner side of the window frame and extending inwardly beyond the adjacent side of the screen, a closure for the opening in the screen slidably mounted upon the bracket, and means carried by said bracket at a point spaced inwardly from the closure for fulcruming the operator.

8. An operator for the movable ventilator of a window having a screen located inwardly of the ventilator and provided with an opening, comprising an arm pivotally connected to the ventilator and extending through the opening in the screen, a bracket secured to the window frame and extending inwardly beyond the adjacent side of the screen, a closure for the opening mounted upon the bracket for sliding movement longitudinally thereof upon actuation of the operator, and means for fulcruming the operator upon the bracket at a point spaced inwardly beyond the closure.

In testimony whereof I affix my signature.

CLYDE W. KELLY.
